UNITED STATES PATENT OFFICE.

ALVA M. HULL, OF DETROIT, MICHIGAN.

COUNTING-MACHINE.

964,782.

Specification of Letters Patent. Patented July 19, 1910.

Application filed April 7, 1909. Serial No. 482,506.

To all whom it may concern:

Be it known that I, ALVA M. HULL, a citizen of the United States, and a resident of Detroit, in the county of Wayne and State 5 of Michigan, have invented a new and Improved Counting-Machine, of which the following is a specification.

This invention relates to mechanism for conveying from a hopper or other receptacle a predetermined number of small objects, such as tablets, pills, or other balls, capsules or screws and depositing them in a box, bottle, can or other container, by means of a disk having perforations to hold the 15 number of such articles desired; and the object of my improvement is to provide a machine of this kind in which the perforations in the disks will all be properly filled, in which the container will be properly positioned to receive the article, and in which covers may be slipped onto the containers when telescoping boxes are employed.

In the accompanying drawings, Figure 1 is a plan of the machine, portions of the conveying disks being broken away to show the chutes underneath and the receiving hoppers being removed from above the disk in the lower half of the figure. Fig. 2 is a plan of a conveying disk and Fig. 2^a a vertical cross section of the same on the line 2—2 of Fig. 2. Fig. 3 is a plan and Fig. 3^a is a cross section of the same on the line 3—3 of Fig. 3. Fig. 4 is a vertical cross section on the line 4—4 of Fig. 7. Fig. 5 is a plan of the box and 35 cover conveying mechanism. Fig. 6 is a detail on a larger scale of the revolving brushes. Fig. 7 is a front view and central vertical section of the machine. Fig. 8 is a rear view of the container conveyors on a larger 40 scale. Figs. 9, 10 and 11 are details of the same. Fig. 12 is a front view of the same.

Similar reference characters refer to like parts throughout the several views.

In the machine illustrated, selecting and 45 conveying devices in duplicate are shown as it has been found that two machine operators can attend to both as easily as to one.

Referring to Fig. 7, 5 is a base having standards 2 mounted thereon, the mechanism 50 in each being practically the same as in the other.

Mounted in bearings 6 is a shaft 7 having tight and loose pulleys 8 and 9 on its outer end. A bevel pinion 11 on the shaft 7 55 meshes with the gear 10 on the shaft 12, freely revoluble in the central line of the

standard. At its upper end, the standard is broadened into a flange 13 to which is secured a circular bottom 14. (Fig. 3). This bottom has secured to it a cylindrical rim 30 16 which carries inwardly projecting cross bars 17. On the inner ends of these cross bars is mounted a second rim 15, held spaced above the bottom 14. The bottom and outer rim 16 form a case to receive the counting 65 device and articles to be counted.

The shaft 12 carries the two collars 20 (Fig. 6) between which is held the perforated disk 21, (Fig. 2) having as many sets of openings 22 as desired. The shape of 70 these openings will depend upon the articles to be boxed, the disks shown in the drawings being especially adapted for capsules. The number of perforations in each set being the predetermined number to be placed in each 75 container. It has been found that with the blank and perforated spaces in each disk of equal area, ample time is given for the operations of the container conveyers. Immediately over the collars 20 is secured a spur 80 gear 24, held in place by the nut 25. Above the nut the shaft 12 serves as a fulcrum of the two armed brush carrier 26.

Secured to lugs 27 on the bottom 14 are the guides 28 for the outer bearings 29 85 of the shafts 30 of the revoluble brushes 31. On the inner ends of these shafts are bevel pinions 37, while the bearings for these inner ends are supplied by the brackets 33 secured to the inner rim 15 by the screws 34. 90 (Fig. 6). Outer and inner bearings are adjustable by the screws 35. Adjustment of these brushes is desirable, for the brushes should be sufficiently near the disk 21 to throw back all articles lying on the disk but 95 sufficiently far away to allow articles in the perforations to remain there undisturbed.

The bevel gears 37 mesh with bevel gears 32 on the vertical shafts 38 mounted in bearings 39 also carried by the brackets 33. On 100 the lower ends of these shafts are the spur pinions 40 which mesh with the spur gear 24 on the vertical shaft 12. A similar bracket 33 carries a similar shaft 38 having a crank 42 at its upper end, the crank 105 pin 43 of which is connected to the pin 44 on the brush carrier 26 by means of the link 45. As a result the two brushes 46 will each swing back and forth through an arc of about sixty degrees in the space between 110 the rims 15 and 16 and between a cross bar 17 and a brush 31. Two hoppers are mount-

ed above each disk 21 and each is formed of outer side 48, inner side 49, ends 50, and a V shaped bottom 51 which practically divides the hopper into two compartments, in 5 the lower edge of each of which is a narrow discharge opening 52.

Looking down on the machine, Fig. 1, the upper disk turns to the right and the lower to the left. The articles will fall on the 10 disk through the first slot 52 and be carried to the space below the upwardly extending bottom 51 where the first brush 46 will sweep them back and forth. Those that still lie on the face of the disk are thrown 15 back by the first revolving brush 31. The second slot 52 is just beyond the first brush 31 and cross bar 17, and the articles delivered are again brushed back and forth by the second swinging brush 46, and the 20 surplus articles are again thrown back by the second revolving brush 31. A second hopper, similar to the first insures all openings being filled, and the last revolving brush prevents articles from lying on top of the 25 disk being carried to the discharging position. When the apertures 22 in the disk pass over the slot 54 in the bottom 14, the articles in the apertures fall into the chute or spout 55 mounted below the bottom, 30 which spouts are preferably made of sheet metal.

Each standard 2 is slotted down the inner side and in this slot is movable a block 58 secured to the cross frame 59 of the container feeding mechanism. The block 58 furnishes a bearing for the hub gear 60, which is slidable on and revolves with the shaft 12. A shaft 61 mounted in the frame 59 carries a bevel gear 62 on its outer end, 40 so that it may mesh with the gear 60, and a spur gear 63 on its inner end, which in turn drives the container feeding mechanism. The cross frame 59 is threaded to receive the screw 64, which has a hand wheel 65 secured to it. By turning this hand wheel the cross frame 59, together with the table 66, which is connected to the cross frame by means of brackets 67, may be raised or lowered to accommodate containers of different 45 sizes.

The front of the table 66 is at the right in Fig. 1. To the table are secured four guides 69 in the form of angle bars by means of the bolts 70. The lugs on these bars have 55 slotted holes so the guides may be adjusted to accommodate containers of different widths. One operator places a container in the front of the space between each pair of guides at regular intervals. At each half 60 revolution of the disk, the feeding mechanism moves these containers under the spouts 55, and at the same time moves the two just filled to the rear end of the machine. The table is formed of front and rear parts, connected by the guide bars 69 as shown in Fig. 65

1, the guide bars having inwardly extending flanges 72, with upper faces flush with the table, to support the containers.

Referring now to Figs. 4, 5, 8 and 12, it being understood that the front of the machine is at the right in Figs. 4 and 5, and that Fig. 12 is a front view of the container feeding device. The rear end of a guide bar 74 is mounted on the pivot 75 carried by the table, and the front end is guided by the 75 lugs 76 and held down by the spring 77. A pin 78 extends downward from the bar 74 and normally rests on the cam 79 on the shaft 80. This shaft is journaled in the bracket 81 carried by the frame 59, and carries a gear 82 at one end, which gear meshes with the gear 63 on the shaft 61. On the opposite end of the shaft, next the cam 79, are the sprocket wheel 83 and crank 84. The sprocket wheel drives the cover convey- 85 ing device. Slidable on the bar 74 is four-armed conveyer 85, two of the arms 86 thereon extending toward the front and two arms 87 toward the rear. An arm 86 and an arm 87 of the conveyer move through the 90 space between each pair of guide bars 69. A pin 88 projects from the side of the conveyer and is connected to the upper end of the lever 89 by means of the link 90. A bracket 91 on the frame 59 supports the 95 lower end of this lever and a link 92 connects it to the crank 84 on the shaft 80. The operations of these parts are as follows, it being understood that the shaft 80 makes one revolution for each half revolution of 100 the disk 21, more particularly, that the conveyer 85 moves toward the rear during the time a blank portion of the disk 21 passes over the slot 54, and moves toward the front during the time a perforated portion of the 105 disk passes over this slot. Gearing may be changed to provide a greater or less number of strokes according to the number of perforated sections.

Fig. 4 shows the conveyer and its operating mechanism in the middle of the rearward stroke, that is, in the middle of its container carrying stroke. The operator having placed a container between each pair of guides 69, they are caught by the lips on 110 the arms 86 and carried rearwardly until they stop under the spouts 55. All of this time the pin 78 rests on the cam 79. At the time containers are being carried to filling position, the rear arms 87 have been 115 pushing the immediately preceding and now filled containers away from the spouts toward the back of the machine. Just as the containers arrive under the spouts, the high portion of the cam 79 passes from 120 under the pin 78, permitting the bar 74 and the conveyer 85 to fall, so that during the return stroke the lips on the arms 86 and 87 will be below the level of the flanges 72 and will therefore pass entirely below the con- 125 130

ainers. At the forward end of the stroke the cam again operates raising the conveyer to operative position to push empty containers under the spouts and full containers to the rear.

As the containers are formed no larger than necessary, it may happen that the contents will heap in the middle and extend upward beyond the top of the sides. In this case the spouts 55 may rake off some of the contents when the filled container is moved away. To prevent this, the spouts are made so the lower parts telescope on the upper, which lower parts are connected by a bar 94. A spring 95 on the conveyer 85 will engage this bar and lift the lower ends of the spouts just as the rear arms 87 engage the filled containers.

Many containers such as bottles and cans will be removed from the machine when they have reached the rear end before being closed. The covers of telescoping boxes can be put in place by the following described mechanism. A bracket 97 extends down from the rear portion of the table and carries a shaft 98 which has a sprocket wheel 99 at one end. A chain 100 connects this wheel with the wheel 83 on the shaft 80. On the shaft 98 next the sprocket wheel is a cam 101, and on the opposite end is a miter gear 102 which meshes with a similar gear 103 on the shaft 104 that is journaled in the bracket 105. This shaft has secured on its opposite end a cam 106 and crank 107.

Mounted at one end on the pin 108 carried by the table, and having its other end resting on the cam 106 is the bar 109 upon which the conveyer 110 is slidable. This conveyer has front arms 111 and rear arms 112 which pass up through slots 113 in the table. A bracket 114 carries a pin 115 at its lower end upon which pin the lever 116 is pivoted. The link 117 connects the upper end of the lever to the conveyer 110, while the link 118 connects the lever and the crank 107 as shown in Fig. 8. To hold the conveyer bar 109 against the cam 106 a spring 119 is provided, which spring is mounted between lugs 120 as shown in Figs. 5 and 8, which lugs also prevent the bar from slipping off the cam. The operation of this conveyer consists in bringing two covers to position where they will lie in line with the filled containers, the arms 111 bringing up the covers for the containers filled from one disk

21 and the arms 112 a cover for the container from the other disk. Covered containers are merely pushed ahead of the covers. The table is made slightly lower at the rear end along the line 145 so the telescope covers will be the thickness of the material below the containers, as shown in Figs. 4, 8 and 10. In Fig. 10, four slots 113 are shown so that when the covers are long, four arms 111 and 112 may be em-

ployed. As it is necessary that the covers be accurately positioned, a conveyer such as shown in Fig. 9 may be employed for long boxes. The body 124 has a pin 125 to engage the link 118. Rods 123 have fingers 70 secured to them by set-screws 127 so that these fingers may be inclined forward or backward so the articles before them may be accurately positioned.

To push the container into its cover an independent mechanism is provided. A bar 130 is pivoted on the table at 131, (Figs. 1 and 4) and on the bar is slidable a conveyer, consisting of a block 132 having arms 133. At the outer end of each arm is mounted a vertical stem having a shoe 134 at its lower end, which shoe has a down-turned flange 135 to engage the rear end of the container. The bar 130 has a pin 136 extending downward into engagement with the cam 101. A lever 137 is pivoted to the lower end of a bracket 138 and connects to the crank 139 by means of the link 140. The upper end of the lever has a slot 142 in which is movable the pin 141 on the block 132. The lever 137 moves through the slot 144 in the table.

When the container and cover have reached the end of the movements received from the conveyers 85 and 110 respectively, these conveyers drop and return. The shoes 95 134 have during this time moved toward the front end of their stroke and they then lower down onto the containers and move with them to the rear, pushing them into the telescope covers. At the end of this stroke the bar 130 rises and the shoes again move toward the front.

Many changes may be made in the details of this construction by those skilled in the art without departing from the spirit of my invention.

Having now explained my construction, what I claim as my invention and desire to secure by Letters Patent is;—

1. In a counting machine, the combination of a frame, a vertical shaft revoluble therein, a slotted plate mounted on the top of the frame, a cylindrical rim on the plate, a perforated disk mounted on the shaft above the plate, a ring and cross-bars carried by the rim to divide the space above the disk into compartments, a brush pivoted on said shaft, and means driven by said shaft to oscillate said brush in one of the compartments.

2. In a counting machine, the combination of a frame comprising a plate having a slot, a vertical shaft mounted in said frame, a perforated disk mounted on said shaft, an oscillating brush movable above the disk to insure the perforations being filled, and means to revolve the shaft and disk to carry the perforations above the slot in the plate.

3. In a counting machine, the combination of a case having a slot, a perforated 130

disk revoluble within the case, a brush to oscillate over the disk to cause the perforations to be filled, and means to revolve the disk and actuate the brush.

5. 4. In a counting machine, the combination of a case having a slot, a perforated disk revoluble within the case, revoluble brushes mounted in pairs over the disk, a brush mounted to swing between each pair 10 of revoluble brushes, and means to actuate the brushes and disk.

5. In a counting machine, the combination of a case having a slot, a perforated disk revoluble within the case, a brush mounted to swing above the disk to cause 15 the perforations to be filled, means to swing the brush and turn the disk so the perforations will pass over the slot, a spout attached to the case below the slot, and conveying 20 means to position containers below said spout.

6. In a counting machine, the combination of a frame, a vertical shaft revoluble therein, a case at the upper end of the frame, 25 a perforated disk mounted on the shaft in said case, a reciprocating arm mounted on the end of the shaft, actuating gearing connecting the shaft and arm, a brush carried by said arm and adapted to swing over the 30 disk to cause the perforations to be filled, said case having a slot through which said perforations may empty, a spout below the slot, and means to position containers below the spout.

35. 7. In a counting machine, the combination of a frame, a shaft revoluble therein, a circular plate secured to the top of the frame, a cylindrical rim on the plate, a perforated disk secured to the shaft above the 40 plate, cross-bars carried by the rim and ex-

tending inwardly, a ring mounted on the ends of the cross bars concentric with the rim, and oscillating brushes mounted on said shaft above the perforated disk between said cross-bars.

45

8. In a counting machine, the combination of a frame, a shaft revoluble therein, a circular plate secured to the top of the frame, a cylindrical rim on the plate, a perforated disk secured to the shaft above the 50 plate, a ring concentric with the rim, cross-bars connecting the rim and ring and supporting the ring above the circular plate, bearings mounted on the rim and ring, revolving brushes extending between said 55 bearings and means connected to the shaft to drive the brushes.

9. In a counting machine, the combination of a frame, a shaft revoluble therein, a circular plate secured to the top of the 60 frame, a cylindrical rim on the plate, a perforated disk secured to the shaft above the plate, a ring concentric with the rim, cross-bars connecting the rim and ring and supporting the ring above the circular plate, revolving brushes extending between and having 65 their bearings mounted on the rim and ring, bevel gears mounted on the brushes and the shaft to drive the brushes, and oscillating brushes mounted on the shaft to swing 70 above the perforated disk between said cross bars.

In testimony whereof I have signed this specification in the presence of two subscribing witnesses.

ALVA M. HULL.
